UNITED STATES PATENT OFFICE.

EVERETT B. GLENDENNING, OF BOSTON, MASSACHUSETTS, BY OPERATION OF LAW
TO RALPH H. CAHOUET, TRUSTEE IN BANKRUPTCY OF McTARNAHAN FUEL OIL
BURNING CORPORATION, OF BOSTON, MASSACHUSETTS, A CORPORATION OF
MASSACHUSETTS.

FUEL-OIL-BURNING APPARATUS.

Application filed December 12, 1923. Serial No. 680,245.

To all whom it may concern:

Be it known that I, EVERETT B. GLENDENNING, a citizen of the United States, residing at Boston, in the county of Suffolk and 5 State of Massachusetts, have invented certain new and useful Improvements in Fuel-Oil-Burning Apparatus, of which the following is a specification.

The invention to be hereinafter described 10 relates to fuel oil burning apparatus, and more particularly to an improvement in burners.

In practice it is necessary from time to time to move the burner to and from active 15 firing position in which its fuel delivery end projects into a furnace. One of the purposes of the invention, therefore, is to provide simple, efficient means for detachably securing the burner or gun on a sup- 20 port.

In the present instance, the gun is of the high pressure type in which the fuel oil is atomized by and mixed with steam or compressed air. The gun has a passage for 25 conducting the fuel oil and a passage for conducting the atomizing fluid, and the support has connected therewith a pipe for conducting fuel oil to the fuel oil passage of the gun, and also connected therewith a pipe 30 for conducting atomizing fluid to the atomizing fluid passage of the gun. Another purpose of the invention is to provide means for preventing leakage of the fuel oil and atomizing fluid passing from the pipes into 35 the passages of the gun.

The gun is slid on and along the support to and from its active firing position. Therefore, another purpose of the invention is to provide means for preventing the sliding 40 movements of the gun from injuring leak preventing gaskets or seats on the support.

After the supply of fuel oil to the gun has been shut off, some residual oil will remain 45 in the oil conducting passages of the gun, and if allowed to remain therein, would become carbonized and objectionably obstruct said passages. Another purpose of the invention, therefore, is to provide simple 50 and efficient means for driving the residual oil from the passages in the gun, thereby to maintain the same clear and unobstructed for efficient operation. In carrying this feature of the invention into practical effect,

in the present instance, the support is provided with a duct and a valve whereby the atomizing fluid may be delivered from the atomizing fluid conducting pipe into the fuel oil conducting passages of the burner thereby to drive the residual oil therefrom. 55

It is desirable that the fuel oil and the atomizing fluid shall be thoroughly mixed, and that the atomizing fluid shall meet the fuel oil with high velocity and desirable distribution, and that the construction shall 60 be such that the flame issuing from the burner shall have wide spread for efficient heating effect. Another purpose of the invention, therefore, is to provide the burner with simple and efficient means for mixing 65 the fuel oil and the atomizing fluid for the purposes above set forth. 70

The character of the invention may be best understood by reference to the following description of one good form thereof 75 shown in the accompanying drawings, wherein:

Fig. 1 is a plan of the apparatus;

Fig. 2 is a side elevation of the apparatus; 80

Fig. 3 is a vertical longitudinal section taken on line 3—3 of Fig. 1;

Fig. 4 is a rear end elevation of the apparatus, certain parts being shown in vertical section; 85

Fig. 5 is a plan of a portion of the support, parts being broken away and other parts being shown in section;

Fig. 6 is a detail of the mixing device; 90

Fig. 7 is a development of the vanes and passages of the mixing device; and

Fig. 8 on an enlarged scale is a front end view of the tip of the gun. 95

Referring to the drawings, the apparatus shown therein as one good form of the invention, comprises a support 1 formed to provide a seat 3, in the present instance, having a flat bottom. At the lower side of the support is a boss 5 having a passage 7, and threaded into said boss is a pipe 9 for 100 conducting fuel oil to the passage 7. Also, projecting from the under side of the support is a boss 11 having a passage 13, and threaded into said boss is a pipe 15 for conducting steam or other atomizing fluid to 105 the passage 13. Projecting from the front end of the support is a curved seat 17, and at one end of this seat is a flange 19, said

- seat 17 and the boss 11 being strengthened by a web 21. Projecting upward from the rear end of the support is a lip or rest 23 for a purpose to be described.
- 5 The burner or gun, in the present instance of the invention, comprises a breech 25 having a flat base 27 and of a length such that it may seat between the flange 19 and the lip 23 of the support. The breech is formed to provide a chamber 27, a fuel oil conducting port or passage 29, and an atomizing fluid conducting port or passage 31. These ports open at one side of the breech.
- 10 15 Threaded into the breech 25 and communicating with the chamber 27, is one end of a barrel or casing 32, and threaded to the opposite end of the barrel is a tip 33 containing a mixing device to be described.
- 20 25 30 Mounted in the barrel is a pipe 35 having one end threaded into the breech and communicating with the fuel oil passage 29 referred to. The pipe 35 is smaller than the barrel 32, and is spaced therefrom to provide an atomizing fluid conducting passage 37. Projecting rearward from the breech, and desirably formed integral therewith, is a handle 38 which may be grasped in moving the gun to and from the support.
- 35 40 45 To prevent the fuel oil flowing from the pipe 9 and the support passage 7 into the gun passage 29, from leaking at the juncture of the breech base with the support, the latter may be provided with a recess 39 surrounding the passage 7 and adapted to receive a gasket 41 of lead or other suitable material. To prevent the atomizing fluid, flowing from the pipe 15 and the support passage 13 into the gun passage 31, from leaking between the base of the gun and the support, the latter may be provided with a recess 43 encircling the passage 13 and receiving the gasket 45 of lead or other suitable material.
- 50 55 60 65 When the gun is to be placed on the support in firing position, the gun is presented to the support so that it rests in inclined position in engagement with the curved seat 17 and the upper edge of the lip 23. The gun is slid forwardly along the seat and lip until the front end of the breech is brought into engagement with the flange 19. Then the rear end of the breech has escaped from the lip 23, and the gun may be rocked down to a horizontal position in which the base of the breech will rest on the gaskets 41 and 43, which serve as a seat.
- 60 65 The means for holding the breech down in tight engagement with the seat, in the present instance of the invention, comprises a yoke 47 having one end pivotally connected by a pin 49 with ears 51 rising from the support. This yoke extends across the breech transversely to the longitudinal axis of the gun, and the opposite end of the yoke is formed to provide a fork 53. A latch device or arm 55 is pivotally connected to the front end of the support by a pin 57, and said arm has a flange 59 and a handle 61. When this arm is rocked to vertical position, it will enter the fork 53, and its flange 59 will be in position to engage the upper side of the fork 53. A screw 63 is threaded into the yoke at a point midway between the ends thereof, and is adapted to engage the top of the breech, said screw being provided with a hand wheel 65.
- 70 75 80 85 90 95 The construction is such that after the gun has been presented to the support as described, the yoke 47 may be rocked over the breech, and the arm 55 may be rocked upward into the fork of the yoke. Then the hand wheel 65 may be turned to rotate the screw 63, and the latter will react on the yoke and press the breech downward so that its bottom is in tight engagement with the gaskets. When it is desired to remove the gun from the support, the screw 63 is released, and the arm 61 is rocked out of the yoke fork, thereby permitting the yoke to be rocked away from the breech, and permitting the gun to be lifted from the support.
- 95 100 105 110 115 120 The means for driving residual oil from the fuel oil passage of the gun, in the present instance, comprises a duct in the support extending between the fuel oil conducting passage 7 and the atomizing fluid conducting passage 13. This duct may be conveniently formed by a bore 67 cutting through the passage 7, a bore 69 cutting through the passage 13, and a bore 71 extending transversely to and connecting the bores 67 and 69, said bore 71 forming a continuation of a larger bore 73. The outer end of the bore 67 may be closed by a plug 75, and the outer end of the bore 69 may be closed by a plug 77.
- 125 130 Threaded in the bore 73 is a gland 79 having a nut 81 formed therein adapted to engage a side of the support. Threaded into the gland is a stem 83 having a tapered end 85 serving as a valve adapted to fit into a similarly shaped seat 87 at one end of the cross bore 71. Fast on the opposite end of the stem is a hand wheel 89. To prevent leakage along the stem, a nut 91 may be threaded on the gland, and may be recessed to receive suitable packing material.
- 130 135 140 145 150 The construction is such that after the supply of fuel oil to the burner has been shut off, the hand wheel 89 may be turned so as to unseat the valve 85 and permit atomizing fluid to pass from the passage 13 through the bores 69, 71 and 67 to the oil conducting passage 7 in the support. The atomizing fluid may pass thence through the port 29 and the pipe 35, and drive out therefrom any residual oil which may remain therein after shutting off the fuel oil.

supply. The fluid will also clear residual fuel oil from the mixing device which will now be described.

The mixing device referred to, in the present instance of the invention, comprises a member 93 having a hollow body 95 of general cylindrical form, and smaller in diameter than the internal diameter of the tip 33 referred to. The body 95 contains a chamber 97 having one end closed and its other end tapped for threaded engagement with the outer end of the fuel oil conducting pipe 35. Projecting outward from the body 95 are ribs or vanes 99 adapted to fit into the tip, and said vanes are tapered to provide converged passages or ducts 101 having medial lines substantially parallel to the longitudinal axis of the barrel 31. Formed in the body at the narrower ends of the converged passages 101 are small holes 103 communicating with the chamber 97. The body 95 projects outward a substantial distance beyond the narrower ends of the converged passages, and has an outward circumferential projection 105. A nut 107 is formed on the outer end of the body, and is adapted to receive a tool for screwing the body onto and off from the pipe 35. The outer end of the tip 35 is slabbed off, and an elongated orifice 109 is formed therein.

The construction of the mixing device is such that the steam flowing through the passage 37 will flow through the converged passages 101, and on issuing therefrom with velocity increased by said passages, will meet the streams of oil issuing through the small holes 103. The oil and atomizing fluid will be effectively mixed, and the oil will be atomized. The circumferential projection 105 will further promote atomization of the oil. The mixture will flow thence out through the orifice 109 and will flare outward and produce a flame of wide spread for efficient heating effect. Since the medial lines of the converged passages 101 are substantially parallel to the longitudinal axis of the gun barrel, the mixed oil and atomizing fluid will not have a whirl or rotative effect, and consequently the flame will have a uniform spread on issuing from the orifice.

It will be understood that the invention is not limited to the specific embodiment shown, and that various deviations may be made therefrom without departing from the spirit and scope of the appended claims.

What is claimed is:

1. Fuel oil burning apparatus comprising, in combination, a support, a fuel oil gun adapted to slide along the support to and from active firing position, said gun and support having passages for conducting fuel oil and atomizing fluid, means to secure the gun to the support with the open ends of the gun passages in registration with the open ends of the support passages, and a

member on the support projecting outward from the plane of the open ends of the support passages and adapted to prevent the gun from engagement with the portion of the support at the open ends of the support 70 passages when the gun is slid along the support to and from firing position.

2. A fuel oil gun comprising, in combination, a breech, a barrel connected to the breech, a pipe in the barrel for conducting 75 fuel oil and spaced from the barrel to provide an atomizing fluid conducting passage, a tip connected to the barrel and having an orifice, and a member mounted in said tip and connected to said pipe, said member 80 having a series of vanes projecting outward therefrom to the inner surface of the tip, said vanes being formed to provide tapered passages converged toward the outer end of the tip and having their medial lines sub- 85 substantially parallel to the longitudinal axis of the barrel, and said member having a passage communicating with the fuel oil pipe and having small holes at the apexes of the converged passages, thereby to deliver fuel 90 oil streams into the atomizing fluid streams emerging from the converged passages.

3. A fuel oil gun comprising, in combination, a breech, a barrel connected to the breech, a pipe in the barrel for conducting 95 fuel oil and spaced therefrom to provide an atomizing fluid conducting passage, a tip connected to the barrel and having an orifice, and means for mixing the fuel oil and the atomizing fluid comprising a hollow 100 member in the tip connected to the pipe and communicating therewith, said member being formed to provide a series of converged passages having their medial lines substantially parallel with the longitudinal axis 105 of the barrel, and said member having holes at the apexes of the converged passages for delivering oil streams to the atomizing fluid streams issuing from the converged 110 passages.

4. A fuel oil gun comprising, in combination, a breech, a barrel connected to the breech, a pipe in the barrel for conducting fuel oil and spaced therefrom to provide an atomizing fluid conducting passage, a tip 115 connected to the barrel and having an orifice, means for mixing the fuel oil and the atomizing fluid comprising a hollow member in the tip connected to the pipe and communicating therewith, said member being formed 120 to provide a series of converged passages having their medial lines substantially parallel with the longitudinal axis of the barrel, and said member having holes at the apexes of the converged passages for delivering oil streams to the atomizing fluid streams issuing from the converged 125 passages, and an outstanding circumferential projection on the member beyond said holes 130 for promoting atomization of the fuel oil.

5. A fuel oil burner comprising, in combination, a casing having fuel oil and atomizing fluid conducting passages, and means for mixing the fuel oil and atomizing fluid comprising a tip having an orifice, a hollow member in the tip communicating with the fuel oil passage, said member having a series of tapered ducts communicating with the fluid passage and the tip, said ducts having their medial lines substantially parallel with the longitudinal axis of the casing, and said member having holes at the apexes of the tapered ducts for delivering oil streams to the fluid streams entering the tip from the ducts.
6. Fuel oil burning apparatus comprising, in combination, a support having a seat, and a pair of passages opening at the seat and adapted for communication with fuel oil and atomizing fluid conducting pipes, a fuel oil gun adapted to slide along said support to and from active firing position on said seat, said gun having a pair of ports at one side thereof for communication with the passages in the support, and means to press the gun tightly against the seat thereby to hold the gun in firing position and prevent leakage at the juncture of the gun ports with the support passages, said support having a lip projecting up from the seat and adapted to prevent the gun from engaging the seat while it is sliding to and from firing position.
7. Fuel oil burning apparatus comprising, in combination, a support having a seat, and a pair of passages opening at the seat and adapted for communication with fuel oil and atomizing fluid conducting pipes, a fuel oil gun having a pair of ports opening at one side of the gun, one of said ports being adapted for communication with one of said passages, and the other port being adapted for communication with the other passage, a yoke pivotally connected to the support and adapted to extend transversely over the side of the gun opposite its port containing side, means to secure the free end of the yoke to the support, and means cooperating with the yoke and the gun for pressing the port containing side of the gun tightly against the seat of the support, said yoke being movable from its secured position to permit the gun to be lifted up from the seat and away from the support.
8. Fuel oil burning apparatus comprising, in combination, a support having a pair of passages adapted for communication with fuel oil and atomizing fluid conducting pipes, a gun having fuel oil and atomizing fluid conducting passages with ports for communication with the passages of the support, and means for clearing residual oil from the gun comprising a pair of straight bores in the support, one of said bores extending transversely to and communicating with one of the support passages, and the other of said bores extending transversely to and communicating with the other support passage, and valve means in the support for establishing communication between said straight bores, thereby to permit the atomizing fluid to pass from the atomizing fluid pipe through said bores into the fuel oil passage of the gun and drive residual oil therefrom.

EVERETT B. GLENDENNING.
